Filed Dec. 22, 1970, Ser. No. 26,613

Term of patent 7 years

Int. Cl. D13—03

U.S. Cl. D26—1 A

FIG. 1

FIG. 5 FIG. 6

FIG. 10

FIG. 1 is a front elevational view of an earth bar showing our new design,

FIG. 2 is a top plan view thereof,

FIG. 3 is a cross-sectional view taken on line III—III of FIG. 1,

FIG. 4 is a bottom plan view thereof,

FIG. 5 is a right side elevational view thereof,

FIG. 6 is a front elevational view showing one variation in our design,

FIG. 7 is a top plan view thereof,

FIG. 8 is a cross-sectional view taken on line VIII—VIII of FIG. 6,

FIG. 9 is a bottom plan view thereof,

FIG. 10 is a right side elevational view thereof.

We claim:

The ornamental design for an earth bar, as shown.
